CUP STORAGE RACK

Louise A. Valletlonga, Northbrook, Ill.

Application June 24, 1957, Serial No. 46,695

Term of patent 14 years

(Cl. D44—29)

Fig. 1 is a bottom plan view of a cup storage rack embodying my design; Fig. 2 is a side elevational view; and Fig. 3 is a top plan view of the same.

I claim:

The ornamental design for a cup storage rack, substantially as shown.
